UNITED STATES PATENT OFFICE.

ANTON BECKER, OF COLUMBUS, OHIO, ASSIGNOR TO THE RALSTON STEEL CAR COMPANY, OF COLUMBUS, OHIO.

CAR END CONSTRUCTION.

1,248,792.

Specification of Letters Patent.

Patented Dec. 4, 1917.

Application filed April 24, 1914, Serial No. 834,170.

To all whom it may concern:

Be it known that I, ANTON BECKER, of Columbus, in the county of Franklin and State of Ohio, have invented certain new and useful Improvements in Car End Constructions; and I do hereby declare the following to be a full, clear, and exact description of the invention, such as will enable others skilled in the art to which it applies to make and use the same.

This invention relates to improvements in end constructions for railroad cars,—the object of the invention being to so construct a corrugated steel car end as to enhance the strength and rigidity of the same throughout its entire width from corner post to corner post, and to reduce liability of deflection.

With this object in view, the invention consists in certain novel features of construction and combinations of parts as hereinafter set forth and pointed out in the claim.

In the accompanying drawings; Figure 1 is a face view of a car-end improvement, and Fig. 2 is a partial side elevation of a car body, giving an edge view of the car end.

1 represents a portion of the framework of a car body; 2 the corner posts, and 3 the end sill.

The car end comprises sheet steel plates 4—5 secured to the framing. I prefer to employ at least two of such sheets,—the lower edge of the upper sheet overlapping the upper edge of the lower sheet and riveted thereto as shown at 6. Each end sheet is provided at its right angles with vertical flanges 7 bent at right angles to the sheet and caused to lie against the outer faces of the corner posts, to which latter they are secured, the flanges of the upper sheet overlapping the flanges of the lower sheet. The lower edge of the lower end sheet 5, is provided with an outwardly projecting flange 8 which is securely riveted to the end sill.

The end sheets 4—5 are corrugated transversely forming a plurality of outwardly projecting V-shaped ribs 9 disposed transversely of the sheets. These ribs or corrugations are made of quite pronounced depth 60 and they extend fully to the side edges of the plates where said side edges unite with the integral side flanges 7. That is to say,—the said ribs or corrugations do not terminate near the extreme side edges of the 65 plates, but extend completely to said side edges so that the ends of the ribs or corrugations will extend to and form parts of the side edges of the plates from which the flanges 7 project. By such construction, the 70 strength of the car end will be greatly enhanced and deflection will be prevented because the ribs will strengthen the plates at their side edges from which the flanges 7 project. Furthermore, the V-shape of the 75 ribs or corrugations will also aid materially in imparting strength and rigidity to the car end.

Having fully described my invention what I claim as new and desire to secure by Letters-Patent, is:—

A sheet metal car end comprising two sheets, each having flanges at its respective side edges to receive fastening means, one of said sheets and its flanges overlapping the other sheet and its flanges and secured together, each of said sheets having a plurality of horizontally disposed parallel outwardly projecting V-shaped ribs or corrugations spaced apart, each rib or corrugation extending continuously across the sheet from one flanged edge to the other thereof.

In testimony whereof, I have signed this specification in the presence of two subscribing witnesses.

ANTON BECKER.
